(57) **CLAIM**

The ornamental design for a nebulizer mask, as shown and described.

DESCRIPTION

FIG. 1 is a top-right perspective view of the nebulizer mask. FIG. 2 is a front elevation view of the nebulizer mask shown in FIG. 1

FIG. 3 is a back elevation view of the nebulizer mask shown in FIG. 1

FIG. 4 is a right elevation view of the nebulizer mask shown in FIG. 1, the left elevation view being a mirror image thereof.

FIG. 5 is a top plan view of the nebulizer mask shown in FIG. 1

FIG. 6 is a bottom plan view of the nebulizer mask shown in FIG. 1; and,

FIG. 7 is a bottom-right perspective view of the nebulizer mask.

The broken lines in the drawings depict portions of the nebulizer mask that form no part of the claimed design.

1 Claim, 7 Drawing Sheets
